UNITED STATES PATENT OFFICE

2.383.858

PENCIL-BONDED MEMORANDUM PAD

Carl C. Harris, Orange, Mass.

Application November 3, 1943, Serial No. 508,813

3 Claims. (Cl. 281—15)

This invention relates to a pencil-bonded memorandum pad and the object thereof is to provide an article of manufacture comprising a pad having a base of suitable, preferably thin, sheet material, with a multiplicity of sheets of writing paper superimposed thereupon with a pencil extending longitudinally of the uppermost sheet having at its upper end a clip of thin resilient material detachably embracing a plurality of superimposed sheets acting to clamp together the pencil and the sheets embraced by the clip, thereby securing the pencil to the pad and causing the pencil to reinforce the pad longitudinally against flexure.

These and other objects and features of the invention will more fully appear from the following description and the accompanying drawing and will be particularly pointed out in the claims.

In the drawing:

Fig. 1 is a perspective view of a preferred embodiment of the invention; and Fig. 2 is a

Fig. 2 is a perspective view of a modified embodiment of the invention and

Fig. 3 is a perspective view of the upper end

Fig. 3 is a perspective view of the upper end portion of a preferred form of pencil and clip for bonding the pencil and a plurality of superimposed sheets to the pad.

A further object of the invention is to provide a pencil-bonded pad of the character above described with a band secured to said base overlying the upper end portions of the sheet and means secured to the base overlying the tapered end of the pencil acting further to bond the pencil to and reinforce the pad, and also to prevent lateral movement of the pencil upon the pad.

The embodiments of the invention illustrated in the drawing comprise broadly a pencil-bonded writing pad having a base of preferably thin sheet material having a multiplicity of sheets of writing paper superimposed thereon with means for retaining the upper ends of the sheet from lateral displacement relatively to the pad and to each other and a pencil having adjacent its upper end a thin resilient clip extending over and detachably embracing the upper ends of a plurality of the superimposed sheets with the tongue thereof clamping the embraced sheets and pencil together in such manner as to hold the pencil firmly upon the pad and thereby to reinforce the pad longitudinally. Preferably means are provided for releasably clamping the lower end of the pencil upon the pad thereby further reinforcing the pad against flexure.

A further object of the invention is to provide a pencil-bonded pad in which the means for releasably securing the tapered end of the pencil to the pad comprises a band secured at its ends and along its lower edge to the pad and overlying the lower ends of the loose sheets of the pad and also overlying the tapered end portion of the tapered end of the pencil.

The pencil-bonded pad construction illustrated in Fig. 1 comprises a base 1, of sheet material, such as leather, cardboard, or the like, of preferably rectangular form of suitable width and length to be readily introduced into the pocket of the user with a multiplicity of narrower sheets 2 of writing paper superimposed thereupon. In the construction illustrated in Fig. 1 the sheets desirably are separate superimposed sheets and the upper ends of the sheets are secured against lateral displacement relatively to the base and to each other by a narrow band 3 of flexible material, such as leather, fabric, paper, or the like, which is secured at its edges by lines of stitching 4 and 5 to the base of the pad, the portion 6 thereof between the lines of stitching having such fullness as to receive the upper ends of the superimposed sheets between it and the base.

Another object of the invention is to provide a pencil-bonded pad of the character above described in which the upper edges of the superimposed sheets, and preferably also the upper band, are provided centrally of their width with alined inwardly extending recesses to receive the tongue of the clip in order that the end of the pencil or an eraser projecting therefrom will not extend beyond the upper edge of the base and the sheets superimposed thereupon.

A further object of the invention is to provide a pencil-bonded pad of the character above described with a supplemental backing sheet secured to the base and forming therewith a pocket to receive sheets having memoranda inscribed thereon which have been removed from the pad and are desired to be preserved.

Another object of the invention is to provide a pencil-bonded pocket pad which can be readily introduced into a pocket without interference by the engagement of the end of the pencil with the wall of the pocket and which can be comfortably carried in the pocket with the base of the pocket adjacent the wearer and without unduly bulging the pocket.

The lower end portion of the pad is similarly provided with a band 7 which is secured to it by a line of stitching 8 extending across one end, continuing across the pad adjacent the lower end thereof and continuing across the opposite end of the band 7. The portion of the band between

the lines of stitching at the ends of the band is likewise provided with sufficient fullness to receive the lower ends of the superimposed sheets and retain them from lateral displacement relatively to the base and to each other and to prevent curling of the corners thereof. Desirably the upper edge of the band 7 is inclined slightly outwardly to facilitate the introduction of the lower end of the pencil beneath the band.

In the construction illustrated in Fig. 1 a supplemental backing member 9 of leather, or other suitable material, is secured to the base 2 of the pad to provide a pocket into which a sheet or sheets of memoranda may be introduced after having been removed from the face of the pad and preserved for future reference. In the preferred construction illustrated the supplemental backing sheet 9 is secured to the base by a line of stitching 10 which extends lengthwise of one side of the pad across the bottom with a continuing portion 11 which extends partway up the opposite longitudinal edge of the pad so that the upper corner portion of the supplemental backing sheet 9 may be separated from the pad, as illustrated in Fig. 1, for the purpose of permitting the sheet or sheets removed from the pad to be easily inserted into the pocket thus provided.

Desirably the central portion of the upper end of the superimposed sheets and also the band 3 are provided with aligned preferably semi-circular recesses 12 to receive the portion of the clip which bonds the pencil to the pad.

Any suitable form of pencil having a clip of thin material may be employed, and the term "pencil" is used herein in a broad sense as defining a manually used writing instrumentality such as a lead pencil preferably a mechanical pencil, a stylographic pen, or the like.

Preferably a thin pencil having a body of rectangular cross section is employed in which one of the flat faces 13 engages the face of the uppermost sheet and the relatively thin sides or edges 14 are of such narrow width as to add but little to the thickness of the pencil-bonded pad.

An automatic mechanical pencil is illustrated in Fig. 1 having a tapered end portion 15 which merges into a conical point section 16 adapted to be rotated to propel and repel the lead 17 as is usual in automatic pencils of this type. As illustrated an eraser 18 is detachably mounted in the upper end of the pencil and a suitable clip is secured to the upper end portion of the pencil.

The pencil and the clip therefor preferably is of the character illustrated and described in my prior application Serial Number 506,146, filed October 14, 1943, which discloses a mechanical pencil having secured at its upper end a clip having legs 19 provided with inwardly turned ends which are pivotally mounted in the narrow sides of the pencil body and extend to or beyond the end of the pencil body and are reversely bent to form open loops 20 which extend a short distance in parallelism with the sides of the pencil and are offset inwardly to provide fulcrum points 21 which cooperate with the flat face of the pencil with an arched tongue 22 extending from said fulcrum points longitudinally of the pencil body well beyond the pivotal points of the legs 19 and provided with a looped end 23 which is slightly bent outwardly to enable the clip to be readily introduced between two adjacent writing sheets of the pad.

As illustrated in Fig. 1 the looped portion of the clip extends beyond the end of the pencil into the recess 12 at the upper end of the pad sufficiently to enable the eraser 18 of the pencil when

attached to the pad to lie within the border of the upper end of the pad while the tongue of the pencil engages a plurality of the superimposed sheets and thereby bonds the upper end of the pad and pencil firmly together. The lower tapered end of the pencil extends beneath the band 7 so that the flat body of the pencil is firmly clamped upon the pad and serves further to reinforce it against flexure.

A modified embodiment of the invention is illustrated in Fig. 2 in which the pad comprises a thin sheet metal base 24 having superimposed thereupon a multiplicity of sheets 25 of writing paper preferably having aligned recesses 26 extending inwardly from the central portion of the pad with the remaining upper ends of the sheets secured together by an adhesive binding 27, or in any other suitable manner, to prevent them from lateral movement relatively to the base and to each other.

In this construction a band 28 encircles the lower end portion of the pad and the free ends of the superimposed sheets and the ends 29 of the band are secured to the base 24 by adhesive or in any suitable manner. In this construction a flat lead pencil, which may be an automatic pencil or a wooden pencil, may be employed and the upper end of the pencil provided with a suitable clip preferably such as shown in Figs. 1 and 3, the lower tapered end of the pencil being retained beneath the band 28 in the manner heretofore described.

Desirably a wire clip, such as is illustrated in Fig. 3, is employed which by reason of the pivotal connection of the legs 19 to the side edges of the pencil and the reversely bent open loops will permit the larger number of sheets to be inserted and clamped upon the pencil than in usual clip constructions. Furthermore in the construction illustrated in Fig. 3 the fulcrum points 21 and the end of the tongue 23 provides a three-point clamping action which will force the body portion of the pencil firmly against the pad and also prevent lateral swinging movement of the pencil which might remove the lower end of the pencil from beneath the lower band.

It will be understood that the particular embodiments of the invention shown and described herein are of an illustrative character and not restrictive of the meaning and scope of the following claims.

Having thus described the invention, what is claimed as new, and desired to be secured by Letters Patent, is:

1. A writing pad comprising a flat base of suitable material, a multiplicity of like sheets uniformly superimposed thereon having midway of the width of their upper ends uniform aligned recesses adapted to receive and enable a resilient pencil clip to embrace a plurality of said sheets, means for preventing relative lateral displacement of said upper ends, and means secured to said base overlying the lower corner portions of said superimposed sheets to prevent relative lateral displacement of the sheets and curling of the corners thereof.

2. A writing pad comprising a flat base of suitable material, a multiplicity of like sheets uniformly superimposed thereon having midway of the width of their upper ends uniform aligned recesses adapted to receive the resilient clip of a mechanical pencil and enable it to embrace a plurality of said sheets, and a narrow band secured to said base embracing the lower end

portion of superimposed sheets and adapted to engage the tapered end of the pencil.

3. A writing pad comprising a flat base of suitable material, a multiplicity of like sheets uniformly superimposed thereon having midway of the width of their upper ends uniform aligned recesses adapted to receive the resilient clip of a mechanical pencil and enable it to embrace a

plurality of said sheets, an adhesive binding securing the remainder of the upper edges of said sheets together and to said base, and means secured to said base overlying the lower corner portions of said superimposed sheets to prevent relative lateral displacement of the sheets and curling of the corners.

CARL C. HARRIS.
